UNITED STATES PATENT OFFICE.

LESTER L. D. ELDERKIN, OF BOSTON, MASSACHUSETTS.

MACHINE FOR GAGING AND DISTRIBUTING ARTICLES OF DIFFERENT THICKNESSES.

1,078,778.

Specification of Letters Patent.

Patented Nov. 18, 1913.

Application filed February 3, 1910. Serial No. 541,778.

To all whom it may concern:

Be it known that I, LESTER L. D. ELDERKIN, of Boston, in the county of Suffolk and State of Massachusetts, have invented certain new and useful Improvements in Machines for Gaging and Distributing Articles of Different Thicknesses, of which the following is a specification.

This invention relates to mechanism for 10 gaging the thickness of various articles and is combined with work-carrying mechanism and with automatic mechanism by which the work-engaging means is caused to discharge or release the articles at various points so 15 that a mass of articles of various thicknesses may be sorted and deposited at different points according to their relative thickness.

In the manufacture of boots and shoes, the 20 blanks of leather which are subsequently incorporated into the boots and shoes as soles and heel-lifts are cut or died from hides which vary in thickness at different points. The result of the cutting or dieing operation is that the soles or lifts become indiscriminately intermingled without regard to their 25 thickness and it is therefore necessary to separate them into various lots, each lot comprising only those soles or lifts which are of approximately equal thickness. Hitherto the separating or sorting of the soles 30 or lifts has been accomplished manually by inserting the articles one by one between co-operative members of a gaging mechanism which is provided with indicating means by 35 which the operator is advised as to the thickness of the article. The operator, after obtaining an indication of the thickness, deposits the article in an appropriate receptacle designated for articles of a 40 particular thickness. The consumption of time and the expense of skilled labor required for sorting articles in this way 45 warrant the provision of a machine which may automatically gage the thickness of the articles introduced to it and carry the articles to various points and discharge them at various points according to their thickness so that all of such articles as are of one thickness may be deposited at one point and 50 those of other thicknesses may be deposited respectively at other points.

To this end the present invention provides a machine combining work-gaging and carrying means for carrying articles of 55 various thickness, and means for effecting the release of the articles by the carrying

means in consequence of which the articles become automatically deposited in separate lots of which each lot receives only those articles which are of approximately equal 60 thickness.

For the purpose of illustration, the accompanying drawings show a machine of the above specified character which is especially adapted to gage and deposit articles 65 such as soles and lifts.

A further object of the invention is to 70 gage the thickness of each article at a plurality of points. This is accomplished by independent calipers whereby the thickness of the article at one of the several points may be gaged independently of the members which engage the article at the other of 75 said points. This feature of the invention is provided especially when the machine is to be employed for assorting soles.

It is customary in selecting a sole to take 80 as the basis of selection the thickness of the sole at the marginal portion of the forepart. If the sole is of the required thickness at the marginal portion of the forepart, the thickness of the other portions of the sole is comparatively unimportant. To those skilled in the art, the reason for selecting a sole according to this basis of comparison is well-known and requires no explanation.

For the purpose, then, of equipping a sorting machine with means for gaging a sole and depositing the sole, solely with regard to the thickness of the marginal portion of the forepart, the present invention provides work-gaging and carrying means including a plurality of separate individual movable jaws or feelers arranged to engage the marginal portion of the forepart of a sole at separate points, said jaws or feelers, however, being related to each other in one sense as a unit and combined with means controlled by any one or all of said jaws or feelers for effecting the retraction of the jaws or feelers and the consequent discharge or release of the sole. It may be desirable to so organize the jaws or feelers as to enable the individual jaw engaging the point of minimum thickness to control the releasing means, whereby the point at which the sole is released and discharged may be determined by that point of the marginal portion of the forepart which is of minimum thickness.

Having provided a machine including the several mechanisms hereinbefore recited, it

is desirable to provide recording means whereby the number of articles discharged at each of the several discharging points, may be recorded. The present invention therefore includes counting devices, one at each of the discharging points, said devices being connected and actuated by the releasing means whereby the number of articles discharged at each point is recorded.

10 Of the accompanying drawings which illustrate a machine for automatically gaging and distributing articles, Figure 1 represents a top plan view of a machine embodying one form and arrangement of mechanisms adapted especially to the gaging and distributing of heel lifts. Fig. 2 represents a vertical section of said machine on line 2—2 of Fig. 1. Fig. 3 represents a horizontal edge elevation of one of the gaging and carrying devices with which the machine is provided. Fig. 4 represents a vertical section on line 4—4 of Fig. 3. Fig. 5 represents a similar vertical section in which the gaging mechanism is in a different position. Fig. 6 represents a vertical section of said machine including means for holding an article in position to be received by the gaging and carrying means. Fig. 7 represents a vertical section of a form of gaging and carrying mechanism especially adapted for gaging the marginal portion of the forepart of a sole. Fig. 8 represents an elevation of the gaging mechanism included in Fig. 7. Fig. 9 represents a plan view of a fragment 35 of the carrying means included in Figs. 7 and 8. Fig. 10 represents an elevation of a shoe sole blank. Fig. 11 represents an elevation of a shoe sole blank. Fig. 12 represents a perspective view of a spring follower.

40 Similar reference characters indicate the same parts wherever they occur.

Referring first to the form illustrated by Figs. 1 to 6 inclusive, the machine consists essentially of a rotary carrier which is 45 mounted to rotate about a vertical axis, and which is rotated by mechanism which renders its rotary movement continuous and uniform. The carrier is substantially circular and at or near its periphery are 50 mounted a series of gaging devices each of which is adapted to receive and carry a single article. The gaging devices therefore move continuously in a circular path and they are supplemented by a series of stationary devices with which the gaging devices 55 are adapted to coöperate to effect the release and discharge of the articles. The several gaging devices are identical in construction and arrangement and the several releasing devices are identical in their operation, but 60 differ slightly in construction and in their arrangement. All of the gaging devices, however, are adapted to coöperate with all of the releasing devices, but the gaging devices are positioned independently of each

other by the several pieces of work and they are therefore controlled by the work and thereby caused to effect selective coöperation with any one of the several releasing devices.

The structure of the machine herein illustrated includes an upstanding base 10 formed with a horizontal shoulder 11 and a cylindrical portion 12 extending vertically. The shoulder 11 and cylindrical portion 12 form bearings for a rotary table or carrier 13 upon which the several gaging devices are mounted. Above the table 13 is arranged a stationary table 14 which, with convenience, may be mounted upon an extension 15 of the central base or standard 10. The table 14 may be affixed to the extension 15 or secured in any other manner to prevent rotation. The means for rotating the table 13 continuously includes a gear 16 affixed to said table, a pinion 17 intermeshed with said gear, a shaft 18 carrying the pinion 17 and also carrying a bevel gear 19. The shaft 18 is journaled in a boss 20 supported by the stationary table 14. The table 14 also supports brackets 21, 21, which furnish bearings for a shaft 22. The shaft 22 is provided with a bevel gear 23 engaging the gear 19 and with one or more pulleys. The drawing includes two pulleys indicated respectively, at 24 and 25, said pulleys being respectively 90 tight and loose, and a belt connected to a source of power.

At the periphery of the rotary table 13 is a series of stationary jaws, each stationary jaw being associated with a movable 100 jaw. The jaws as shown by the drawings comprise depending blocks or plates 26 and adjustable screw-headed studs 27 carried by said plates. These jaws are preferably arranged equi-distantly around the periphery 105 of the table and may be more or less in number than those shown. The number provided for the machine illustrated is eight. The screws 27 extend inwardly and radially and their inner ends constitute abutments 110 which engage one surface of a lift to be gaged. The opposite surface of the lift is engaged by a movable jaw 28 arranged in a recess in the table 13 and mounted upon a pivot stud 29. The axis of the stud 29 115 extends substantially parallel to the direction in which it moves when the carriage rotates, and the jaw 28 depending therefrom is therefore adapted to move radially with relation to the carriage when approaching the stationary jaw. The work-engaging surfaces of the stationary and movable jaws are substantially parallel to their direction of carrying movement and a lift such as that indicated at α , Figs. 3 and 125 4 when held by and between the jaws, is held in a vertical position with its broad surfaces extending substantially parallel to the direction in which the lift is carried. Each movable jaw 28 is provided with an 130

upwardly extending arm 30 which carries one of the members of the gaging mechanism hereinafter described. Springs 31 connected to the arms 30 exert their tension to close the jaws 28 and the lifts which are introduced between the coöperative jaws are supported by reason of the yielding tension due to said springs.

At the point where the lifts are introduced to the machine, it may be desirable to provide a device for holding the lifts one at a time, until they are grasped and removed by the carrying jaws. A device for this purpose is illustrated by Fig. 6 and includes a fixed arm 32 and a stationary spring arm 33 arranged to coöperate with the end of the arm 32. The abutting ends of the two arms meet at a point slightly below the horizontal plane of the work-engaging jaws and they are so arranged as to permit insertion of a lift by an upward edgewise movement of the lift. The spring arm 33 is here shown as supported by a bracket 34, affixed to the central standard 10. A lift may be inserted between and held by the arms 32 and 33 at any time and the next pair of jaws to arrive at the point where the lift is so supported is initially opened, the movable jaw 28 being permitted to close in response to the tension of its spring 31, in passing the lift held between the arms. In this way the lift is grasped by the jaws and is carried edgewise and removed from the supporting arms and continues to be carried by the jaws until the movable jaw is subsequently opened against the tension of its spring 31.

Referring now to Fig. 1, it will be seen that the reference characters A, B, C, H, I and J are arranged in an arc concentric to the axis of rotation of the table 13. The letter A indicates the receiving point, or in other words, the point at which the lifts are introduced to the machine. The direction of rotation of the table 13 is indicated by an arrow and the lifts grasped by the jaws 27, 28, are therefore carried to points B, C, H, I and J, and to such intermediate points as are presumably included for a complete machine. The letter B is used here to represent the first of a series of points of discharge and the remaining letters indicate the succeeding points of discharge. The points designated by the letters B to J inclusive may, if desired, be considered as representing receptacles for the reception of the lifts which are discharged. The releasing mechanism by which the movable jaws 28 are opened comprises a detector at the upper end of each of the arms 30 and a series of actuating members pivotally mounted upon the stationary table 14, and arranged to be engaged by the detectors. The positions of the several detectors are of course deter-

mined by the thickness of the lifts in the jaws and the actuators which are engaged by the detectors are preferably arranged to effect the release of lifts of minimum thickness at receptacle B and the release of the lifts of greater thickness at the successive receptacles according to the relative thickness of the lifts so that the lifts of maximum thickness may pass all of the intermediate receptacles and be discharged at the last receptacle of the series at J.

The construction of one of the detectors is illustrated by Figs. 2 to 5 inclusive. The detectors are indicated at 35. They are secured at the upper ends of the arms 30 by screws or bolts 36 which extend through slots 37 in said arms. The slots permit adjustability of the detectors in a direction toward or from the axis of the table 13 and the adjustment may be determined by set screws 38. The operative portion of each detector is pointed as shown in plan view by Fig. 1. The detectors point in the direction of rotation of the table and they are so positioned by reason of the thickness of the lifts between the jaws that they move in a circle of relatively short radius when controlled by a relatively thin lift and in a circle of relatively great radius when controlled by a lift of maximum thickness. The actuators by which the jaws are opened at the several points of discharge are indicated respectively at b, c, d, h, i, and j. The several actuators are of the same general character but are here shown as differing slightly in shape. The positions of the successive actuators are graduated so as to effect the release of the lifts of minimum thickness at B and of the lifts of greater thickness at the successive points according to their thickness. The several actuators are pivotally mounted upon pins or studs 40. The studs extend vertically and the actuators are therefore adapted to swing in a horizontal plane when engaged by the detectors. Each actuator is initially positioned by a set screw 41 and is normally held against its set screw by a spring 42. The actuators are preferably pointed and arranged to normally extend in the direction opposite to the direction of rotation of the table 13. The point of the actuator b is relatively near the axis of rotation and the positions of the points of the successive actuators are graduated so that each succeeding point is slightly farther from the axis of rotation than the preceding point. The detector 35 carried by a movable jaw which is engaging a lift of minimum thickness, is positioned by the lift so that it is within the radius of the point of the actuator b. The detector therefore impinges against the actuator thereby swinging the actuator outwardly about its pivot 40. The point of the actuator enters a recess in the detector and

the detector is therefore moved outwardly by reason of the swinging of the actuator. In this way, the arm 30 is retracted against the tension of its spring 31 and the movable 5 jaw 28 is separated from the lift so that the lift becomes released and may drop into the receptacle B. When the detector has so far advanced as to leave the actuator b, the latter is returned by its spring 42 to its stop 10 41 in which position it is ready to be engaged by any subsequent detector. The detector of a jaw 28 engaging a lift of materially greater thickness is positioned by the lift so as to avoid the actuator b and the 15 lift is therefore carried to one of the subsequent points of discharge, the point of discharge being determined by the coöperation of the detector with the first actuator lying in its path. Each movable jaw 28, upon 20 being opened, is locked in open position by a detent shown in the form of a spring follower 43. (See Figs. 3, 4 and 5). A spring follower is provided for each of the jaws 28. Said followers are mounted in brackets 44, 25 mounted upon the rotary table 13, and they are engaged by springs 43^a which normally tend to move them toward the arms 30. Each arm is provided with a plate 46, said plate presenting a shoulder 45, (Fig. 2) which co- 30 operates with the follower. When the jaw 28 is closed as shown by Fig. 4, the end of the follower 43 abuts against the side of the plate 46 and does not interfere with the opening of the jaw. When the arm 30 is 35 retracted against the tension of the spring 31, the end of the plate 46 passes beyond the follower 43 and the follower is there- upon projected in front of the shoulder 45 and locks the jaw in open position. All of the 40 jaws which are opened as the result of the action of the actuators b, c, etc., remain locked in open position until they once more arrive at the receiving point indicated at A. The actuator j is so formed as to effect 45 the opening of all of the jaws which are not opened by the preceding actuators and for this reason it is not necessary to provide an adjustable stop for the actuator j nor a spring for normally holding it in one position. The actuator j may therefore re- 50 main stationary at all times and effect the opening of the jaws by reason of its inclined surface j' which is adapted to deflect the detectors which engage it. The jaws ap- 55 proaching the receiving point A are therefore always open to receive a lift at the point A.

When the jaws arrive at point A their spring followers 43 are automatically re- 60 tracted so that they may be closed by their springs 31. The means here shown for effecting the retraction of the followers is shown by Fig. 1. The followers are engaged by bell-cranks 50, each bell-crank being pivotally mounted at 51. The bell-crank of each

follower engages shoulders formed upon the follower as the result of providing a recess 52 in the follower for the reception of the bell-crank. The bell-cranks are provided with blocks 53 which engage a stationary 70 cam 54 mounted upon the table 14. The cam 54 is so arranged as to effect a movement of each successive bell-crank 50 to retract the follower 43 when the jaws 27, 28 are on opposite sides of a lift held by the stationary 75 arms 32, 33. If, for any reason, there is no lift in the arms 32, 33, when a pair of jaws is passing said arms, the movable jaw is closed as if there were in fact a lift at that point. All of such jaws as pass point A 80 without receiving a lift are opened by the first of the series of actuators. It is apparent therefore that the actuator b may be encountered as well by detectors of empty jaws as by detectors of jaws carrying lifts 85 of minimum thickness.

It is desirable to count the number of lifts discharged at each point. Counting devices are therefore provided, each of said devices being connected to an actuator to count the 90 number of releasing movements of the actuator. With regard now to the actuators, it will be seen by reference to Fig. 1 that each is connected with a rod. The rods are indicated respectively at c², d², h², i². The several rods are connected to arms c³, d³, h³ and i³ of individual meters or indicating devices. The meters are indicated respectively at c⁴, d⁴, h⁴ and i⁴. Their particular construction and mode of operation are imma- 95 terial inasmuch as any suitable device may be employed for the purpose.

The table 13 may be provided with seg- 100 mental strips 55 of angular cross section, the horizontal lips of said strips serving as stops or gages for determining as shown by Fig. 4 the horizontal plane of the lifts which are inserted at A between the arms 32, 33. The strips 55 are arranged intermediately with 105 relation to the several pairs of jaws 27, 28, and they may substantially fill the space between the pairs of jaws so that a lift moved upwardly between the arms 32, 33 at any 110 time may encounter the horizontal lip of any one of the said strips.

When the machine is to be employed for 115 gaging and distributing soles instead of heel lifts, the jaws 27, 28, may be omitted and other means of a somewhat different character may be substituted for gaging the marginal portion of the forepart of a sole. Before passing to a description of the gaging mechanism for gaging a sole, it will be well to refer to Fig. 10 of the drawings which 120 illustrates a blank sole y. When the sole-gaging devices hereinafter described are substituted for the jaws 27, 28 it is proposed to arrange them so that they will be adapted to receive and carry a sole y in substantially 125 the same relative position as that in which 130

the lifts α are carried by the jaws 27, 28. It is proposed to insert a sole γ in the gaging devices with the forepart uppermost as shown by Fig. 10, the heel part being left entirely free from engagement with the machine. For the reception of the forepart, the table 13 may be provided with a structure such as that shown by Figs. 7, 8 and 9. In these figures, brackets such as that indicated at 60 are adjustably attached to the periphery of the table by means of screws 61 which extend through recesses 62 formed in the brackets. Each bracket is attached at one side only and is formed to provide a space 10 at 63 for the reception of the sole γ . A bracket 60 serves as a jaw against which the outer surface of the sole γ may be pressed and the present invention provides a plurality of complementary jaws or feelers for each jaw 15 60, said feelers being arranged to engage the inner surface of the sole and to press against the sole with yielding tension. The several feelers of one group are indicated in Figs. 7 and 8 at 64^a, 64^b, and 64^c and 65^a, 65^b, and 20 65^c. The table 13 is provided with recesses 64 and 65 for the reception of the jaws or feelers which as shown are arranged in two subgroups. The several feelers are arranged to engage the marginal portion of the fore- 25 part of a sole at the points indicated in Fig. 10 at 4^a, 4^b, 4^c and 5^a, 5^b and 5^c, respectively. This arrangement may be varied unreservedly, and the present invention intends to include every possible arrangement and 30 number of feelers. For example, Fig. 11 illustrates the several points of contact at an equal distance from the edge of the sole. For the sake of convenience in organizing the several feelers, they may be pivotally 35 mounted upon a common pivot stud 66, arranged in brackets 67 upon the table 13. The several feelers are provided with individual springs 68 by which they are normally held against the inner surface of the 40 sole γ .

It is the purpose of the present invention to provide gaging mechanism for each set of feelers, said gaging mechanism to be controlled by the feeler which engages the point 45 of minimum thickness. With each set of feelers is associated an arm 130 which serves the same purpose as the arm 30 in the structure provided for gaging and distributing heel lifts. In the present form, the arm 130 is mounted upon a pivot stud 129, and extends upwardly. A spring 131 connected to the arm 130 tends to move the arm away from the axis of rotation of the table 13. At the upper end of the arm 130 is a detector 50 135 which may be in all respects similar to the detectors 35. The detector 135 may cooperate with a series of actuators in all respects like the actuators hereinbefore described and indicated at b , c , d , h , i and j . 55 The arm 130 may also be provided with a

plate 146 to be engaged by a locking bolt or follower 143, like the follower 43. The upper ends of the feelers are held against a plate 70 affixed upon one end of a bar 71. The bar 71 is pivoted at 72 to the arm 130 and 70 is likewise pivoted at 73 to a link 74 mounted upon a pivot stud 75. The radius of the link 74 is equal to the radius of the arm 130 with regard to the distance of the pivot 72 from the pivot 129. The distance between 75 the pivots 72 and 73 is equal to the distance between the pivots 75 and 129 and the bar 71 may therefore receive an oscillatory motion similar to that of a parallel ruler.

The outer surface of the plate 70 is parallel to the work-engaging surface of the abutment 60 and the area of the plate 70 is such as to coöperate with the upper ends of all of the feelers. As shown by Fig. 7, the feelers are pivoted midway between their extremities and a movement imparted to the lower end of any one of the feelers produces an equal movement at the upper end. The feelers therefore act with equal effect upon the plate 70 even though their lengths vary. 80 If it is desired to amplify the movement of the detector the feelers may be pivoted nearer their work-engaging ends. In that event they may have separate pivots. It may be here stated that the spring 131 is 85 relatively light and may be overpowered by any one of the springs 68, the purpose of providing the spring 131 is chiefly to take up lost motion in the joints of the several pivots so that the moving parts may not rattle and 90 so that the detector may operate with precision. The arms 30 in the form first described, and the arms 130 in the latter form, are analogous to pointers or indicators. It is apparent that they would serve the purpose of indicators if they were arranged to coöperate with dials instead of the actuators b , c , d , etc.

The mode of retracting the bolt or follower 143 may be in all respects like that 110 prescribed for the retraction of the bolts 43 so that a sole may be automatically engaged by the feelers at the receiving point in the rotation of the table 13. When the feelers are released so that they may engage the sole 115 with yielding tension, the feeler which engages the point of minimum thickness will be displaced more than the other feelers and the plate 70 will therefore be displaced and positioned by the feeler engaging the point 120 of minimum thickness. The position of the detector 135 is therefore determined by the feeler which engages the point of minimum thickness and the coöoperative engagement by the detector with any one of a series of 125 actuators b , c , d , h , i , j , will therefore control the releasing of the sole in the same manner as that prescribed for the releasing of a heel lift. As here shown the circuit-engaging surface of the abutment 60 is plane, 130

but if desired the abutment 60 may be provided with small protuberances opposite the several feelers. Said protuberances may be either formed integrally with the abutment 5 60 or they may be afforded by individually adjustable set screws, (not shown).

It is not intended that the present invention should be limited to the specific details of construction and arrangement, for 10 various departures may be made within the spirit and scope of the invention. For example, since the machine comprises calipers, and receptacles, it is obvious that either may be moved with relation to the other to provide for the deposit of the articles in the receptacles.

The operation of the machine is as follows:—The articles to be calipered are inserted between the caliper members at 20 point A (Fig. 1), the caliper members at this point being released by the stationary cam 54 so that their closing springs 31 may close them. Each article thus gripped by the caliper members is carried thereby 25 until the caliper members are opened by the appropriate actuator in the series *b*, *c*, *d*, and so forth, the actuator which becomes effective being determined, as hereinbefore described, by the thickness of the article in 30 the calipers. When the calipers are opened the article is discharged and the calipers are locked in full open position by their respective spring followers 43, so that they may not cause the operation of any other actuators which they may pass before completing 35 a cycle. As each empty caliper device arrives at point A, its spring follower 43 is retracted by the cam 54 as aforesaid, and the caliper members may then be closed 40 again by their closing spring 31 to grip another article. The operation of all the caliper devices is the same as that just described, each device being permitted to close at the point A and each being opened 45 to discharge an article according to its thickness at one of the several discharging points indicated. Each counting device counts only the number of articles discharged at the corresponding point.

50 The term "calipers" as used in the following claims, is used in its broad sense wherever the function of the jaws or feelers does not depend upon opening or closing movement.

55 Having thus explained the nature of my said invention and described a way of making and using the same, although without attempting to set forth all of the forms in which it may be made or all of the modes of 60 its use, I declare that what I claim is:

1. A machine of the character described comprising feelers for engaging one side of a piece of work at a plurality of points, means for engaging the opposite side of the 65 work in coactive relation with said feelers,

and means for effecting separation of said feelers and said coacting means, said means being controlled through the medium of the feeler or feelers nearest said coacting means.

2. A machine of the character described 70 comprising feelers for engaging one side of the work at a plurality of points, a jaw for engaging the opposite side of the work, and means for retracting all of said feelers, said means being controlled through the medium 75 of one of said feelers.

3. A machine of the character described comprising a carrier, caliper jaws carried by said carrier, a detector, means for transmitting movement from one of said jaws to 80 said detector to position the detector, and a series of actuators for opening said jaws, each of said actuators being arranged to be operatively moved by said detector upon movement of the carrier.

4. A machine of the character described comprising a carrier, a plurality of sets of caliper jaws carried by said carrier, a plurality of detectors, one for each set of 90 said jaws, means for transmitting movement from said jaws to said detectors to position said detectors, and a series of movable members arranged to be engaged and moved singly by any one of said detectors, each of 95 said movable members being adapted to coact with said detectors to open said jaws completely.

5. A machine of the character described comprising a carrier, a plurality of sets of caliper jaws carried by said carrier, a plurality of detectors, one for each set of 100 said jaws, means for transmitting movement from the jaws of each set to the detector of each set to position said detectors, a series of movable members adapted to be severally 105 moved by and to severally move said detectors, said movable members being adapted to open said jaws completely at points corresponding to the location of the several movable members, and means for adjusting 110 said movable members to vary their range of coaction with said detectors.

6. A machine of the character described comprising a carrier, a plurality of sets of spring-closed caliper jaws carried thereby, a plurality of detectors, connections between said sets of jaws and said detectors whereby said jaws may position said detectors, a plurality of means for completely 115 opening each set of said jaws at any one of a plurality of points, said means being determined and operated by said detectors, detents for holding the retracted jaws in open position, and means for moving said detents to release said retracted jaws.

7. A machine of the character described comprising a plurality of feelers for engaging one side of a piece of work at a plurality of points, a jaw for engaging the opposite side of the work, a movable support 125

for said feelers and jaw whereby they are moved with the work while engaging the same, and means controlled by the feeler or feelers engaging the thinnest part of the work for retracting them all from the work.

8. A machine for carrying and distributing articles according to their thickness, said machine comprising a plurality of moving feelers, spring tensioned means for causing said feelers to engage one side of an article, means for engaging the other side of the article in coactive relation with said feelers so as to support and carry the article, and means controlled by one of said feelers for effecting separation of said feelers and said coactive means to release the article.

9. A machine of the character described comprising caliper members for supporting an article, a plurality of said members being disposed to engage one side of such article to caliper a plurality of portions of the same, a movable support for said members, and means controlled by one of said members for retracting them to release the article.

10. A machine of the character described comprising caliper members, a plurality of which are disposed to engage one side of an article to caliper a plurality of portions of such article, and means controlled by one of said members for retracting them to release the article.

11. A machine of the character described comprising caliper members a plurality of which are disposed to engage one side of an article to caliper a plurality of portions of such article, and means controlled by a caliper member engaging the thinnest portion for opening the caliper members to release the article.

12. A machine of the character described comprising an abutment for engaging one side of the work, a plurality of independently movable caliper members for engaging the opposite side of the work at separate points of the same, means for moving said

work-engaging members with the work, and means controlled by the caliper member engaging the work at the thinnest point for opening the work-engaging members to release the work.

13. A machine of the character described comprising calipers for measuring the thickness of an article, a detector connected with the calipers to be positioned by one of the members thereof, a series of members, each adapted to coact with said detector to open said calipers, driving means for causing relative movement of said detector and said series of members to effect coaction of the detector with one of said members, and adjusting means for each of said members whereby any one of them may be rendered operative or inoperative.

14. A machine of the character described comprising a carrier, means carried by said carrier for grasping a piece of work, detecting means, means adapted to be positioned by said grasping means to position said detecting means, and a series of movable members arranged to be engaged and moved by said detecting means, each of said members being adapted to move said detecting means, said positioning means, and said grasping means to effect the release of the work.

15. A machine for gaging and distributing articles, comprising a plurality of co-operative members for engaging opposite sides of an article, a plurality of said members being disposed to engage one side of the article, yielding means for causing said members to engage the article with yielding force, and means controlled by one of said members for opening said members to release the article.

In testimony whereof I have affixed my signature, in presence of two witnesses.

LESTER L. D. ELDERKIN.

Witnesses:

MAURICE CALUCE,
Wm. J. COSTELLO.
